SHIP STABILIZER

Louis A. Occhetti, Bloomfield, N.J., assignor to Lidgerwood Manufacturing Company, New York, N.Y., a corporation of New York

Filed Jan. 2, 1964, Ser. No. 335,231

2 Claims. (Cl. 114—126)

This invention relates to ship stabilization by means of the familiar fins mounted to protrude from the sides of a ship's hull below the water line and to be tilted oppositely to counteract roll.

The main object of the invention is to provide a stabilizer unit of such simplified and improved construction as to be economical to fabricate and to afford numerous advantages from the standpoint of installation and maintenance.

Other objects and advantages of the invention will be apparent from the following description of the accompanying drawings, in which:

FIG. 1 is a partially broken out view in vertical section of a stabilizer installation incorporating a preferred form of the invention, the section being on the line 1—1 of FIG. 2;

FIG. 2 is a sectional view on the line 2—2 of FIG. 1, on a slightly reduced scale; and

FIG. 3 is an enlarged fragmentary view of a detail.

In the illustrated preferred form, the invention is incorporated in a stabilizer installation of the so-called retractable type in which each fin, with its supporting shaft, is bodily rotatable about a stowing axis normal to the tile axis, from an outboard, active position to an idle or stowed position within the lines of the hull. As will later be apparent, various forms and applications of the invention other than the one illustrated are feasible.

The stabilizer fin 1 is secured to a fin shaft 2 which is journaled in bearings 3, 4. These bearings are disposed and supported in the openings 5, 6 formed in the opposite ends of a casting in the form of a shell or hollow body generally designated 10. The inboard shell opening 5 is closed by a bolted cover 11 and the axial thrust of the fin shaft is taken by the shell through bushings 12, 13 disposed on opposite sides of a thrust plate 14 bolted or otherwise secured to the inboard end of the fin shaft.

According to the invention, the tilting of the shaft 2 about its axis, thereby to position the fin as required to stabilize the vessel, is effected by suitable motor means mounted in the shell 10 and preferably such means are hydraulic.

In the form illustrated, the shell 10 is cast with a laterally projecting enlargement or cavity 19 (FIG. 2) accommodating a power cylinder 20, one end of which is pivotally secured, as at 21, to the cavity wall. The free end 22 of cylinder rod 23 is pinned to a crank member 24 bolted to shaft 2. The hydraulic fluid lines connected to opposite ends of the cylinder are indicated at 25 and 26.

This preferred form of the invention incorporates, also mounted within the shell 10, locking means for locking the shaft against tilting as and when required. As shown, such means consists of a bolt or stop 30 rotatably mounted in the upstanding boss 31 and a pair of bars 32 secured to the fin shaft. As will be apparent, by rotating the bolt it can be caused to enter between and engage the bars 32 to lock the fin shaft against tilting or can be withdrawn from such engagement to permit the shaft to be tilted by the motor means.

It will be recognized that the foregoing components are adapted for assembly wherever convenient to form a "package" or unit ready for installation.

In FIG. 1 of the drawings, such a unit is shown installed in a ship's hull in such fashion as to be bodily rotatable about the axis represented by the section line

2

2—2, from the indicated outboard position of the fin to a position in which the fin is stowed within the lines of the hull.

The stowing of fins in this general fashion is well known and, as usual, there is provided a fin box 35 located within and secured to the hull, portions of which are indicated at 36, 37. As is customary, a slot 38 is provided (in this instance shown as formed in the outer wall 39 of the fin box) by way of which the fin enters the box when the unit is rotated with the fin in its median or non-tilted position—which is the position in which the fin may be locked by the locking means described above.

The unit shell 10 is provided with large upper and lower ports or circular openings 45, 46 and the walls of the shell surrounding these ports are bolted, as at 47, to the inner ends of hollow, cylindrical pintle members 48, 49 which project into the hull where their open ends are closed by cover plates 50, 51. Being of like internal diameter to that of the ports, the pintle members form cylindrical extensions of the port openings and provide ready access, from within the hull, to bolts 47. The pintle members are journaled in bushing rings 52, 53 located in the upper and lower walls of the fin box and appropriately secured and braced.

While the stowing mechanism forms no part of the present invention, the bodily rotation of the shell unit and pintle members may be affected by a hydraulic cylinder and rod 60, 61, the latter pinned to a crank member 62 bolted to the upper end of pintle member 48, as indicated in FIG. 2. As also indicated in FIG. 2, the locking member 30 may be operated by a rod 63 extended through the lower cover plate 51 for manipulation by a hand wheel 64 within the hull. It will also be understood, of course, that the hydraulic fluid lines 25, 26 of the fin shaft tilting cylinder 20 are extended out through the shell for connection to a pump (not shown) within the hull.

It will be seen that by providing the large upper and lower shell ports 45, 46 and keeping them unobstructed by disposing the motor means for tilting the fin shaft within the shell, these ports provide ready access to the interior of the shell. Whether the ship is at sea or in dock, it is simply necessary to remove, say, the upper cover plate 50, to bring within reach (for adjustment or repair) the glands, bearings and other components within the shell 10. Emergency repairs can thus be made without requiring any major dismantling of the installation and accordingly at considerable saving of time and expense. While there is nothing critical about the dimensions, it may be noted in this connection that in a typical installation, the diameter of the fin shaft 2 might be of the order of 16" and, at the scale of the drawings, the shell port diameters would be 2' or more; in other words, substantially larger than the shaft diameter.

As shown in FIG. 2, the ports are located, respectively, directly above and beneath the shaft, that is to say, with the port axis intersecting the shaft axis; and since the port (and shell) diameters are substantially greater than the shaft diameter, there is thus created a working space extending from the port openings to and around the sides of the shaft. By this means, as shown in FIG. 1, the adjacent shaft bearings are accessible to be worked on and also, of course, the shaft tilting ram and its rod connection to the shaft.

It will also be noted that as a further result of the illustrated construction the pintle member bearings are of large diameter and, accordingly, the stresses minimized by distributing the pintle reaction forces over large bearing areas.

Still another advantage of the invention is the ease with which the shell unit can be removed bodily for major overhaul or replacement, it being merely necessary to remove bolts 47 and slightly spread the pintle members.

It will be understood that while the above description of the presently preferred form of construction exemplifies the principles of the invention, it is capable of embodiment in various other forms to meet the needs of the particular case; and, in the light of the foregoing, the following is claimed:

1. In a ship stabilizer installation of the retractable fin type including a fin box secured to the hull, a stabilizer unit shell disposed within the box and having aligned upper and lower ports, aligned openings at opposite ends of the shell, bearings in said openings, a fin shaft traversing the shell and journaled in said bearings, upper and lower hollow cylindrical pindle members aligned with said ports and secured to the shell, said members being journaled in and protruding through the fin box walls within the hull, the improvement which comprises: shaft-tilting motor means located within the shell and means within the shell coupling the motor means to the shaft, the axis of the said ports positioned to intersect the axis of the shaft and the diameters of the ports and of the shell portion traversed by the shaft exceeding that of the shaft, whereby a working space is created extending from the port openings to and around the sides of the shaft, the inner ends of the bearings located adjacent said working space, and removable cover plates normally closing the remote

10

ends of the pindle members, the said ports and pindle members being dimensioned to afford access to said working space upon removal of said cover plates.

2. A stabilizer unit comprising a shell having upper and lower aligned ports, aligned openings at opposite ends of the shell, bearings in said openings, a fin shaft traversing the shell and journaled in said bearings, the axis of the ports being located to intersect the axis of the shaft and the diameters of the ports and of the shell portion traversed by the shaft exceeding that of the shaft, whereby a working space is created extending from the port openings to and around the shaft, the inner ends of the shaft bearings being located in said working space and the ports being dimensioned to afford access to said working space.
